UNITED STATES PATENT OFFICE.

PAUL MAUSER, OF OBERNDORF-ON-THE-NECKAR, WÜRTTEMBERG, GERMANY.

MAGAZINE FIRE-ARM.

SPECIFICATION forming part of Letters Patent No. 289,113, dated November 27, 1883.

Application filed June 3, 1881. (No model.) Patented in Belgium April 15, 1881, No. 54,214; in Austria-Hungary June 4, 1881, No. 10,562 and No. 18,608; in France June 10, 1881, No. 141,979; in England June 23, 1881, No. 1,343; in Italy June 30, 1881, No. 12,804; in Spain July 13, 1881, No. 1,578, and in Germany September 17, 1881, No. 15,202.

To all whom it may concern:

Be it known that I, PAUL MAUSER, of Oberndorf-on-the-Neckar, in the Kingdom of Württemberg, German Empire, have invented an Improvement in Repeating Fire-Arms, of which the following is a full and clear specification.

The invention relates to that class of guns which are closed by a cylindrical breech-piece whose locking and firing mechanism is known under the name "Mauser," and in which the cartridge-holding magazine is situated beneath and along the barrel.

The object of the invention is to furnish a device by the application of which to guns of the mentioned pattern these guns may be used at will either as repeating or as single-shot arms.

In the accompanying drawings, in which similar letters indicate like parts, Figures 1 to 8 represent a new gun constructed according to the present invention; Figs. 9 to 12, a modification of certain parts, and Figs. 13 and 14 show the application of the invention to an old gun of the so-called "pattern 71." Fig. 1 is a longitudinal vertical section, the breech closed; Fig. 2, partly the same section, partly a side view, the breech opened; Fig. 3, a horizontal section from below, in the line A B C D E of Fig. 1. Figs. 4, 5, 6 are cross-sections in the lines F G H I K L of Fig. 3. Fig. 7 is an elevation of the left side, partly in section; Fig. 8, a horizontal longitudinal section of the extractor. Figs. 9, 10, 11, 12 show sections and views of some of the improved parts constructed differently from the same parts in the previous figures. Fig. 13 is a horizontal longitudinal section of a gun of the pattern 71, altered according to the present invention and with open breech; Fig. 14, a vertical cross-section in the line M N of Fig. 13.

The main feature of the improved arm is a cartridge-carrier, *b*, oscillating on its rear end and brought in action, when wanted, by the movements of the breech-piece or lock *f*. This carrier *b*, when standing in a downward inclined position, receives the cartridge *a* from the magazine arranged beneath and along the barrel, and delivers it to the barrel when lift-

ed in an upward inclined position. The carrier *b* is lifted and depressed by the movement 50 of the lock *f*, the front end of which serves as a breech-block, and which contains and commands the firing-bolt. During the lifting motion of the carrier the next cartridge *a* of the magazine is stopped and retained by a tail-piece, *h*, of the carrier *b*. When the carrier *b* occupies its lowest position this cartridge is impelled by the driving-spring of the magazine up into the scooped-out bed of the carrier *b*. The following cartridge is stopped by the 55 projection *d* of a spring, *e*. When the carrier *b* is lifted it presses back the spring *e* by means of its swell *m* and liberates the cartridge, allowing it to move to the tail-piece *h*, which stops it again until the next depression of the 60 carrier *b*.

On the rear of the carrier *b* is mounted a block, *i*, sliding up and down in a dovetailed groove of the carrier. When the block *i* is in its highest position its top portion, *k*, is rocked 70 to and fro by shoulders or projections *p* and *q* of the extractor *o*, which latter is fixed to the lock *f* and moves with it. This rocking motion causes the front end of the carrier *b* to rise when the lock *f* is moved backward and the 75 breech opened, and to fall when the lock *f* is moved forward and the breech closed. The extractor *o* is not integral with the lock *f*, although it is attached to and moves with it. Being made separate, it is capable of removal 80 and replacement, and when worn or injured it may be removed. When the sliding block *i* is depressed, so that its top, *k*, is out of reach of the shoulders *p* *q*, the carrier *b* will not be moved—that is to say, the repeater is converted into a single-shot gun. It is important to stop the movement of the carrier *b* when it is raised, forming in this position a smooth bottom in the chamber *e* best adapted to introduce into the barrel a cartridge when loading by hand. To accomplish these objects the sliding block *i* is depressed by a pin, *r*, on the end of the shorter arm of a bell-crank lever, *s*, swinging round the screw-pin *t*. The longer arm of the bell-crank lever protrudes on the 95 side of the chamber *e*, and is shifted into the

required position by hand by means of the thumb-piece *u* of the arm *s*. The pin *v* works in a horizontal slot of the slide-block *i*. The shifting of the lever *s*, and thereby the depressing of *i*, is performed when the carrier *b* is in its highest position, when the block is drawn back for loading. The sliding block *i* rests in its lowest position with its lower back edge against an offset, *x*, provided on the inside of the chamber or case *c*, so as to fix the carrier *b* in its elevated position, prohibiting its being depressed until the sliding block *i* is again raised, liberating at once the carrier *b* and transforming the single-shot gun again into a repeater.

The spring *e* is furnished beside the swell *m* in the front end with a second similar swell, *n*, on the back end. The latter exerts a uniform spring-pressure against the carrier *b* at its fulcrum *g*, while the swell *m* performs the same duty as soon as the front end of the carrier *b* has left its lowest position. By this arrangement the movement of the carrier *b* is made smooth and easy. To show that, and also how the construction of the details can be altered without leaving the ground of the invention, a modification of those parts which control the movements of the carrier *b* is shown in Figs. 9 to 12. The slide-block *i* is not guided by a dovetailed groove of the carrier *b*, but by a square one, and it is moved up and down not by a pin, but by the direct contact of the shorter arm *v'* of the bell-crank lever. This arm *v'* works in a suitably-shaped recess of the block *i*, and swings, together with the longer arm *s*, around the screw-bolt *g t*, by means of which and of the coupled hubs *g* of the two levers *v'* and *s*, these latter are united to a solid piece. The arm *v'* works on the left side of the gun, while the arm *s* protrudes on the right side, so that it can be moved to and fro by means of its thumb-piece *u*. In this way the slide-block *i* is moved up and down, presenting its top *k* to the shoulders *p* and *q* of the extractor *o*, or bringing it out of reach of them, exactly as it is described already above. The carrier *b* swings here not directly round the screw-threaded end, but round the hubs *g t* of the lever *v'* *s*, which turn on the screw-threaded end. The recess of the block *i* is large enough to clear the hubs *g* in any position. By this construction the carrier *b* is very strong, compact, and handy for the user of the arm.

The invention can be applied also to old guns of the so-called "pattern 71." Such is represented in Figs. 13 and 14.

The carrier *b* contains in a recess at the rear the sliding block *i*, the top *k* of which works, when raised, in the groove of the lock *f*, in which works also the trigger-catch. The carrier *b* turns round the screw-bolt *g t*, which forms at the same time the fulcrum of the bell-crank lever *v' s*. The pin of the short arm *v'* works through a slot in the side of the carrier *b*, in a groove of the block *i*, which is allowed to rise and fall. The extractor *o* is not altered at all in this construction, but is that of the old gun. I do not bind myself to one form of the parts.

I claim as my invention—

1. In a repeating fire-arm with cylinder-lock, the longitudinally-sliding extractor *o*, having shoulders *p q*, in combination with the vertically-sliding block *i*, having a top piece, *k*, and with the carrier *b*, substantially as shown and described.

2. In a repeating fire-arm with cylinder-lock, the bell-crank lever *s*, in combination with the vertically-sliding piece *i k*, moving up and down in ways on the carrier adapted to move it into and out of engagement with the shoulders *p q*, carried on the sliding lock *f*, as shown and described.

3. The offset *x* formed on the chamber *C*, in combination with the sliding piece *i* working on the side of the carrier, and with said carrier *b* adapted to lock the latter in its elevated position by the depression of the slide-piece *i*, as herein specified.

4. The spring *e*, furnished with the swells *m* and *n* and head *d*, in combination with the carrier *b* of a repeating fire-arm and with the breech piece or lock *f*, as shown and described, and adapted for joint operation, substantially as set forth.

5. The carrier *b*, governed by the slide-block *i*, acting in the rear end thereof to tilt it, and having the top piece, *k*, on which act the shoulders *p q* of the extractor *o*, or the equivalent devices of the lock *f*, in combination with said lock *f* and with the spring *e*, with its swells *m n* and head *d*, all working together as described, and for the purpose explained.

This specification signed by me this 5th day of February, 1881.

PAUL MAUSER.
